UNITED STATES PATENT OFFICE.

JOHN GIRARD, OF NEW BRITAIN, CONNECTICUT, ASSIGNOR TO LANDERS,
FRARY & CLARK, OF SAME PLACE.

DESIGN FOR DRAWER-PULL.

Specification forming part of Design No. **7,386**, dated April 21, 1874; application filed April 10, 1874.
[Term of Patent 7 years.]

To all whom it may concern:

Be it known that I, JOHN GIRARD, of New Britain, in the county of Hartford and State of Connecticut, have invented a new Design for Drawer-Pull; and I do hereby declare the following, when taken in connection with the accompanying drawing and the letters of reference marked thereon, to be a full, clear, and exact description of the same, and which said drawing constitutes part of this specification, and represents a front view.

This invention relates to a design for that class of drawer-pulls which are of substantially shell shape, having a recess beneath into which to insert the fingers; and it consists in the configuration of the pull, as shown in the

accompanying illustration, and hereinafter described.

The ends at the extreme are vertical, the top a segment from end to end, the whole contracting toward the front. The ends are open, so as to form seats for the screws within the outline of the rear, as shown in the illustration.

The ornamentation is no part of the design.

I claim as my invention—

The design for drawer-pull, as herein described, and shown in the accompanying illustration.

Witnesses: JOHN GIRARD.
